UNITED STATES PATENT OFFICE.

FREDERICK DOUGLAS TAYLOR, OF PROVIDENCE, RHODE ISLAND.

TIDE-MOTOR.

1,047,591.

Specification of Letters Patent.

Patented Dec. 17, 1912.

Application filed April 4, 1912. Serial No. 688,448.

To all whom it may concern:

Be it known that I, FREDERICK D. TAYLOR, a citizen of the United States, and a resident of Providence, in the county of Providence and State of Rhode Island, have invented a new and Improved Tide-Motor, of which the following is a full, clear, and exact description.

This invention relates to hydraulic motors and particularly to power devices of this type which are adapted to utilize the force of both the ebb and flow of the tide, the particular object of the invention being to so improve this class of devices as to produce one which will be thoroughly reliable under all of the variable conditions of the source of power. This and other objects are attained in a preferred embodiment by means hereinafter fully described and claimed and illustrated in the accompanying drawings, where on the said figures corresponding parts are referred to by similar reference characters, and in which—

Figure 1 is a plan view, partly in section and partly broken away, of this invention; Fig. 2 is a vertical transverse section substantially on the line 2—2 of Fig. 3; Fig. 3 is a fragmentary side elevation, partly in section, substantially on the line 3—3 of Fig. 1; Fig. 4 is a side elevation in detail of a part of the stationary abutment and gates coöperating therewith; Fig. 5 is a detail of the means for operating said gates; Fig. 6 is a detailed end view, partly in section, of one of the water wheels and associated parts; and Fig. 7 is a perspective view relating to the same detail.

In carrying this invention into practice there is constructed at any convenient place, such for instance as at the mouth of a bay, inlet, or river, a fixed abutment 10 of a height preferably slightly below the water line at low tide and of any length desired, depending upon the location and the amount of power to be developed, said abutment preferably extending entirely across the mouth of the channel at such location. Associated with said abutment 10 is a structure 11 comprising a floating body 12 including frame members 13 and 14 extending laterally therefrom. The float 12 may comprise any desired number of compartments adapted to be loaded with water or other weights so as to bring the top of the float down toward the surface of the water,

as for instance so that the frame members 13 may substantially coincide with said surface. I have indicated, at 15, valves whereby the water may be introduced into the compartments. The upper portion of the abutment 10 may be provided with openings 10^a for the purpose of admitting certain of the float frame members, and with metal strips 10^b.

On each side of the float 12 is provided a dam 16 securely connected to the frame members 13 and 14, whereby the dams 16 will be subjected to the buoyant action of the float 12. It will be understood that one of said dams will be on the outside of the structure and the other on the inside or toward the land. The upper edge of each dam is designed to project slightly above the normal low tide level, say two feet, but I am to be understood as not wishing to be limited in this respect to any particular dimensions. There will also be built upon and carried by the float frame a suitable superstructure or housing 17 within which the operating parts of the motor will be housed, and they, with the operators, will be protected from the severe weather. Each dam may have anti-friction rollers 16^a bearing upon strips 10^b.

The abutment 10 is preferably made as shown in Figs. 2 and 4, and is provided with a central longitudinal chamber 18 and a series of passageways 19 communicating with said chamber from both sides of the abutment. Said passageways 19 are designed to be closed by movable gates 20 arranged substantially water-tight and adapted to be operated from within the housing by any suitable means. As indicated, these gates are arranged vertically and are adapted to slide transversely of the respective passageways along the walls of the abutment 10 by means of racks 21 and pinions 22 connected to upright shafts 23. These shafts extend upwardly through quills 24 carried by the float 12 and are shown as each being provided with a groove or keyway 23^a into which a key or feather 25 carried by a hand wheel 26 extends. The hand wheel is supported rotarily upon the upper end of the adjacent quill 24 and since the float is subjected to variations in tide level the structure above described will provide that the shafts 23 may be held in the abutment structure from vertical movement, and the hand wheels 26

90

110

will always be within easy reach of an attendant on the float 12.

On each side of the housing 17 is provided a series of openings 27 which will be 5 guarded by as many slideable doors 28 and which, when opened, will permit the water to enter the housing and flow within the chamber 18 of the abutment. Each of said openings 27 is preferably guarded by a grating or network 29 to prevent floating obstacles from entering and damaging the interior mechanism.

The operation of the device thus far described is substantially as follows: Assuming 15 that the right hand portion of Fig. 2 is the side toward the sea and the tide is flowing, the water will enter the housing as indicated by the arrows and will flow from the chamber 18 outward toward the left through 20 the open passageways 19, the passageways on the outside being closed at such time by the gates 20. Assuming that the tide is rising there will be a period of an hour or two in which the water will be rising toward the 25 top of the dam 16, and the gates 20 and the dam on the sea-side of the structure at such time will prevent the level of the water on the inside from rising with the tide until after such rise is reached as will cause the 30 water to flow over the dam and into and through the chamber 18 as above set forth.

The force of the water flowing into the housing may be utilized by any suitable mechanism, that herein shown comprising 35 one or more undershot water-wheels 30 arranged directly in front of the aforesaid openings 27. The water flowing over the dam will be received by paddles or buckets 31 and will cause the water-wheels to rotate 40 powerfully in the direction indicated by the arrows. Such power from the water-wheels may be utilized in any convenient way and for any suitable purpose, and I have indicated a series of sprocket wheels 32 connected 45 by sprocket chains 33 to similar sprocket wheels 34 connected to a countershaft 35 journaled in any suitable bearings on the framework of the housing. On said countershaft 35 are secured a set of pulleys 37 50 geared by high speed belt gearing to one or more dynamos 38 from which the generated power may be conveyed to any desired distance.

The water-wheels 30 are connected to a 55 main power shaft 39 journaled in the bearings on the float framework and whose ends extend into fixed inclosures 40, preferably at each end of the abutment 10. Each of the inclosures 40 contains an auxiliary float 41 60 within the water-tight compartments 42 of which there is provided working space for large power pulleys 43 from which other dynamos 44 may be operated by direct belt connections 45. The float 41 may have as 65 many valves 46 as may be necessary to ad-

mit the water or other ballast so as to insure equalization of buoyancy between the main float 12 and the auxiliary floats 41.

After as much inflow of the tide as possible can be utilized in the manner above suggested, the gates 20 on the outside of the abutment 10 will be opened, and after the level of the water is equalized on both sides, all of the gates and doors on the inside or landside of the structure will be closed, 70 maintaining the high level of water on the landside of the device until the ebbing tide will permit the housing and floats to sink low enough so as to make the fall of water over the dam on the landside available for 80 operation of the water-wheels on that side of the motor. The operation from this point will be a duplication of that previously described during the flow of the tide. While there is an interval of an hour or two 85 during each reversal of the tide when this device will not be operative, it is to be understood that since the time of tide at one place is several hours different from that of another place not many hundred miles distant, it is quite possible for cities to be connected by a single system whereby the motors may be operated at different places in 90 relays and thus provide constant power for the supply of said cities and any intermediate connections, or a storage system may be used so as to provide constant power at 95 any station.

The fixed abutments will preferably be constructed of concrete in any approved 100 modern method, although it is to be understood that any suitable materials may be employed for this purpose or in the construction of any of the other parts of this device. Furthermore, I desire not to be 105 limited to the specific details of construction illustrated except as may be required by the state of the art.

Having thus described my invention, what I claim as new and desire to secure by Letters Patent is:

1. The herein described tide motor comprising a fixed abutment below normal low tide level and having a longitudinal central chamber and lateral passage-ways communicating therefrom to both sides of the abutment, sets of gates adapted to close said passage-ways, a floating structure comprising a pair of dams on the opposite sides of said abutment, means to control the flow of 115 water over either of said dams into the chamber aforesaid and thence outwardly through the passageways on the opposite side, and power devices carried by the floating structure to utilize the force of the water 120 flowing into said chamber.

2. The herein described tide motor comprising a main fixed abutment, one or more auxiliary abutments at the ends of the first abutment, a series of floats within the afore- 125

said abutments, said floats having means for equalizing their buoyancy, a pair of dams supported by said floats and means coöperating therewith to control the flow of water 5 at intervals over said dams, a power shaft adjacent the upper edge of each of said dams and journaled upon all of said floats, means carried by the floats to utilize the power derived from the water, and means 10 connecting said power shafts with said power utilizing means.

3. The herein described tide motor comprising a fixed abutment having a series of passageways therethrough, gates adapted to 15 control the passage of water through said passageways, a float associated with said abutment, a series of shafts for operating said gates and fixed from vertical movement and extending upwardly through said float, 20 and means carried at a uniform elevation on said float for operating said gate controlling shafts during all changes in elevation of the float.

4. In a tide motor, the combination of an 25 abutment having a central longitudinal

chamber and passageways leading outwardly therefrom, means to control the passage of water through said passageways, a floating structure embracing said abutment, a pair of dams carried by said float structure 30 and maintained thereby at a certain definite relation to said abutment to control the flow of water over the same and into said chamber, said structure including a series of openings adjacent the upper edges 35 of said dams, means to control the passage of water through said openings, water power devices carried upon said floating structure and adapted to utilize the force of the flowing water aforesaid, and high speed 40 power means to utilize the force of said water power devices.

In testimony whereof I have signed my name to this specification in the presence of two subscribing witnesses.

FREDERICK DOUGLAS TAYLOR.
